UNITED STATES PATENT OFFICE

JAMES D. LE VAN, OF MILWAUKEE, WISCONSIN, ASSIGNOR TO CUTLER-HAMMER, INC.,
OF MILWAUKEE, WISCONSIN, A CORPORATION OF DELAWARE

METHOD OF AND APPARATUS FOR MANUFACTURE OF VACUUM TUBES

Application filed December 26, 1929. Serial No. 416,429.

This invention relates to a method and apparatus particularly advantageous for use in the manufacture of vacuum tubes containing mercury or other liquid.

5 In the past it has been the practice to exhaust such tubes after introduction therein of the desired liquid. Such method has the disadvantage that the mercury or other liquid as introduced has air or other gases 10 trapped therein, with the result that such gases may be liberated during use of the tube and interfere with its operation. Furthermore it is often desirable to heat the tube during exhaustion and such heating vaporizes the mercury and permits some of it to 15 escape as vapor through the exhaust connection so that it is difficult to provide with certainty the proper amount of mercury in the finished tube.

0 The present invention has among its objects to provide for introduction of the mercury or other liquid after exhaustion of the tube and for prior exhaustion of the liquid.

The accompanying drawing illustrates 5 schematically apparatus by means of which a tube may be conveniently exhausted and subsequently supplied with liquid in accordance with the method constituting part of this invention.

0 In the drawing, 1 is a tube which is to be exhausted and into which mercury is to be introduced after the proper degree of vacuum is attained. The exhaust opening of the tube is welded or otherwise connected in the usual manner to the exhaust main 2—3 which is provided with an enlargement 4 at the point of connection of the tube. A vessel 5 which is partly filled with mercury 6 is connected by a downwardly inclined conduit 7 with the enlargement 4 of the exhaust conduit. The conduit 7 communicates with vessel 5 at a point slightly above the normal level of the mercury and is preferably welded to the vessel and to the exhaust conduit.

5 Floating on the mercury is a cylindrical body 8 of glass or other material, of which at least a part 9 is of magnetic material. The vessel 5 is surrounded by a magnet coil 10 and a battery 11 provides for energization of said coil upon closure of a switch 12.

The vessel 5 is provided with an opening 13 through which the mercury may be replenished, said opening being normally closed by the stop cock 14.

With this apparatus it will be apparent that as the tube 1 is being exhausted the vessel 5 is likewise being exhausted as is also the mercury trapped in the vessel 5. Further, it will be apparent that after exhaustion of the tube and vessel to the desired degree 55 the desired amount of mercury may be transferred to the tube by forcing the float into the mercury to displace the latter for overflow thereof into conduit 7. This may be accomplished by closure of switch 12 to energize winding 10 which thereupon will act to draw downwardly its magnetic core 9, thereby raising the level of the mercury for flow of mercury into the tube. The amount of mercury which flows into the tube may be 60 regulated by regulating the strength of the current in the coil 10 in any well known manner or by mounting the coil 10 slidably and moving it downward a given distance, corresponding to the amount of mercury to be 65 transferred.

What I claim as new and desire to secure by Letters Patent is:

1. Apparatus for use in the manufacture of vacuum tubes containing a liquid, comprising a liquid containing vessel to be connected to the tube for exhaustion therewith, said vessel having the liquid contained therein trapped against escape during the exhausting operation and having electromagnetic means to effect transfer of a given amount of said liquid to said tube at will. 80

2. Apparatus for use in the manufacture of vacuum tubes containing a liquid, comprising a vessel to be connected to the tube for exhaustion therewith, said vessel having an open chamber to receive a liquid and to trap the same against flow to said tube during the exhausting operation and electromagnetic means associated with said vessel 85 and controllable at will to effect displacement of the liquid for flow of a given quantity thereof into the tube.

3. Apparatus for use in the manufacture of vacuum tubes containing a liquid, comprising 95

- a vessel to be connected with the tube for exhaustion therewith, said vessel having an open chamber to contain a liquid and to trap the same during exhausting operation and a
5 float within the liquid containing chamber of said vessel having control means whereby it may be actuated at will to displace the liquid for flow of a given quantity thereof into the tube while in exhausted state.
- 10 4. Apparatus for use in the manufacture of vacuum tubes containing a liquid, comprising a vessel to be connected with the tube for exhaustion therewith, said vessel having an open chamber to contain a liquid and to
15 trap the same during exhausting operation and an electromagnet having a winding external to said vessel and a magnetic core within said vessel whereby the liquid in said vessel may be displaced for flow of a given quantity thereof into the tube while maintained
20 in an exhausted state.

In witness whereof, I have hereunto subscribed my name,

JAMES D. LE VAN.
